UNITED STATES PATENT OFFICE.

EMIL FUCHS, OF NEW YORK, N. Y., ASSIGNOR TO CARTIER, INC., OF NEW YORK, N. Y.,
A CORPORATION OF NEW YORK.

DESIGN FOR A SPOON OR SIMILAR ARTICLE.

Application filed March 3, 1922. Serial No. 994. Term of patent 7 years.

To all whom it may concern:

Be it known that I, EMIL FUCHS, a subject of the King of England, residing at New York city, in the county of New York and State of New York, have invented a new, original, and ornamental Design for a Spoon or Similar Article, of which the following is a specification, reference being had to the accompanying drawing, forming part thereof.

Figure 1 is a front view of a spoon or similar article, showing my new design.

Figure 2 is a back view of the spoon or similar article shown in Figure 1; and

Figure 3 is a side elevation of the spoon or similar article.

I claim:

The ornamental design for a spoon or similar article, as shown.

EMIL FUCHS.
